UNITED STATES PATENT OFFICE.

GURNEY WILLIAM KENNEDY, OF QUINCY, FLORIDA.

MACHINE FOR STRINGING TOBACCO LEAVES.

Application filed July 31, 1925. Serial No. 47,314.

This invention relates to machines for stringing tobacco leaves and has for one of its objects the construction of a device of the class designated, in which the needle remains stationary throughout the stringing operation, the tobacco being forced over the needle upon the string by a reciprocating shuttle.

Another object of the invention is the provision of a spacing device for spacing the tobacco at uniform intervals along the string, the operation of which is dependent upon the presence of a unit of tobacco (leaf or leaves) between the shuttle and needle point.

A further object of the invention is to provide an adjustable spacing device that can be set to space the tobacco at any desired intervals.

Other objects of the invention will appear as the following description of an illustrative embodiment thereof proceeds.

In the drawings:—

Figure 1 is a side elevation of an embodiment of the invention;

Figure 2 is a side sectional view of a part of the device, on an enlarged scale;

Figure 3 is a section taken along the line 3—3 of Fig. 2;

Figure 4 is a section taken along the line 4—4 of Fig. 2;

Figure 5 is a perspective view of a portion of the spacing clips about to assume an extended position;

Figures 6, 7 and 8 are perspective views of the front end of the shuttle showing the pushing pawl respectively in inoperative and operative position;

Figures 9 and 10 are perspective views showing alternative forms of the eye of the needle;

Figure 11 is a side elevation of the spacing bar, part thereof being broken away;

Figure 12 is a transverse section through the needle, feed, shuttle and spacing bar chambers, part of the last named chamber being omitted;

Figure 13 is a transverse section on an enlarged scale, through the needle chamber, showing a portion of the needle, and resilient bed therefor;

Figure 14 is an end view of the machine shown in Fig. 1;

Figure 15 is a perspective view showing one of the springs, forming the needle bed;

Figure 16 is a longitudinal section through

the automatic spacing attachment used alternatively to the spacing bar, and

Figure 17 is a section taken along the line 17—17 of Fig. 16.

Referring now in detail to the several figures, the numeral 1 represents a longitudinally extending frame having suitable supports 2 and 3 adjacent the ends thereof. The frame is so constructed as to define spaces which may be differentiated into several chambers, according to their function; a string chamber extending between the end wall 4 and a point in the frame indicated by the reference character "a"; a needle chamber, 70 between the points "a" and "b"; a feed chamber into which the tobacco leaves to be strung are introduced, lying between the points "b" and "c"; and a shuttle chamber extending rearwardly of the feed chamber. The string, needle and feed chambers, are closed at the back but formed with a continuous open bottom. The string chamber is open on the forward side also, as is the feed chamber, but the needle chamber is closed on its forward side by a removable door 27 about which more will be written later. The shuttle chamber may be closed on all sides but on account of the narrowness of the frame, as shown, it has slotted top and bottom walls to accommodate the angular amplitude of travel of the pitman 7.

A needle 8 is stationarily held in the needle chamber, having its point directed toward the feed chamber. The opposite end of the needle is provided with an eye for attaching the string 9. Said string extends through the string chamber, being maintained taut by a weight 10 depending from the opposite end. A shuttle 23 reciprocates in the forward end of the shuttle chamber, and the range of its excursion carries it to a point slightly beyond the eye of the needle. The shuttle is operated by an electric motor 12 or other power source, the power from which is transmitted to a pulley 13 having a crank arm 14. The pitman 7 connects the shuttle 11 with the crank arm 14.

In operating the device, a leaf of tobacco, or a desired number of leaves, is introduced into the feed chamber in front of the needle point, the shuttle operating to force the leaf or bundle of leaves upon the needle and beyond it to a point upon the string adjacent the eye of the needle. Successive leaves or bundles of leaves, as strung, are progressively spaced at equal intervals along the string

2
by means of spacing clips 15 carried by a spacing bar 16, the latter being slidably mounted longitudinally of the frame in an elongated chamber which lies back of the 5 string, needle, and feed chambers, and part of the shuttle chamber. This elongated chamber is defined by the back wall 17 and the intermediate partition 34, seen in section in Figs. 3 and 4. The spacing clips normally 10 lie flat against the spacing bar and come out one at a time as the spacing bar advances behind the leaf or leaves of tobacco which have been deposited by the shuttle adjacent the eye of the needle. The clips 15 act as conveyors in moving the strung leaf or leaves progressively away from the point where they are originally deposited. When 15 filled, the string with the tobacco suspended therefrom at spaced intervals, is removed 20 from the machine and taken to a curing shed, to be hung up until cured.

In proceeding to a description of the details of construction by which these results are produced, it is to be understood that the 25 specific means employed are illustrative only of numerous alternative arrangements of parts or substitution of mechanical equivalents for accomplishing the same or similar purpose.

30 The needle 8 is of the stationary type. It is resiliently held in a bed comprising a plurality of pairs of oppositely arranged springs 19 having concave end pieces 20 which embrace the shank of the needle on opposite 35 sides at a plurality of points. In order that the needle may be positively held against endwise movement, so that the string 9 may be maintained taut, the needle is provided with one or more holes 21, longitudinally arranged, and the springs with blades 22 which enter said holes and positively latch 40 said needle against endwise movement. The co-operating blades 22 which enter a single hole, are so formed that a portion of each 45 extends clear through the hole in which it operates, from side to side thereof, functioning to clear the hole of any gum or other substance deposited by the tobacco in its passage along the needle. The springs 19 are 50 preferably carried by removable members 26 and 27, the latter acting as a door for the needle chamber. The eye of the needle may be of any approved construction, two forms being shown, in Figs. 9 and 10, the eye consisting 55 essentially of a slot into which the string may be passed from the side of the needle, means being provided for engaging and retaining a knot placed in the end of the string.

60 The shuttle 23 is formed with upper and lower portions 50 and 51 respectively, spaced so as to leave an intermediate transverse slot 24 extending the full width thereof and telescoping over both the needle 8 and springs 19 when the shuttle moves to advanced posi-

tion. Said portions carry telescopic noses 52 and 53 respectively, which are limited in their range of telescopic movement by a pin 54, playing in the slots 55. Said noses are secured together by means such as the brace 70 56, so as to operate in unison. They normally assume a forward position being pushed forwardly by the pin 31, which makes contact with a projection 57 carried by the nose 52, upon retrograde movement of 75 the shuttle.

The noses 52 and 53 are preferably formed with V-shaped recesses which engage the tobacco leaf, which are manually presented to the feed chamber, above and below the plane 80 of the needle, as the shuttle transects said feed chamber, impaling it upon the needle. The converging sides of said recess and the oppositely convergent first pair of springs 19, co-operate in allocating the tobacco in a 85 central position with respect to the needle, ensuring that it will be pierced by the latter.

The upper portion 50 of the shuttle is formed with vertical slots 58 and 58' transected by the pin 54 upon which are pivotally mounted the pawls 60 and 61. Said pawls are capable of dropping through said slots to a position in which their lower ends extend below the plane of the needle supporting springs, but in the forward position of the nose 52, said pawls are retained above the plane of said springs by the interposition of the imperforate portion 62 of the floor of said nose. However, the forward portion of said floor is formed with slots 63 and 64 which register with the slots 58 and 58' when the nose 52 is pushed back by contact with the tobacco, letting the pawls drop to spring-engaging position. The purpose of the pawls is to separate the springs progressively ahead of the tobacco as the latter is moved along the needle by the shuttle, and although the tobacco is in advance of the pawls, at the shuttle, the pawls are of such width and the springs of such curvature that said springs 95 are opened by said pawls before the tobacco reaches the apex of the angles between the springs of the successive pairs. The pawls thus make way for the tobacco by pushing apart the springs, successively forcing them 100 away from the needle and the blades thereof out of the holes in the needle, one pair closing in on the needle again before the next pair is released. There is a sufficient number of pairs of springs to ensure the holding 105 of the needle in stationary position, while any one pair is released to permit the tobacco to pass.

110 It will be observed from Figs. 6, 7 and 8 that the portion 50 of the shuttle which lies above the slot 24 is furnished with a pawl 115 28 which normally rests upon an extension 65 of the floor of the telescopic nose 52. Said extension terminates substantially in a transverse plane which reaches the begin- 120 130

ning of the slots 63 and 64 so that the pawl 28 falls off of said extension at about the same time the pawls 60 and 61 drop into spring engaging position; when the nose is 5 pushed back by the tobacco. The function of the pawl 28 is to actuate the spacing mechanism, in a manner which will be presently explained. The shuttle and the part of the frame with which it co-operates are 10 formed with interdigitating sides 32 and guide grooves 33.

It is generally essential in the curing of tobacco that the leaves be uniformly spaced on the string in order to be properly ventilated. The spacing may, however, vary according to several factors among which may be mentioned the humidity of the atmosphere, the condition of the green tobacco, the construction of the shed in which the 20 drying takes place, the amount to be cured, and the grade sought.

In the present invention I have provided the spacing bar 16, previously incidentally referred to, which travels longitudinally in 25 a chamber extending practically the length of the whole machine, to one side of the string, needle, feed, and shuttle chambers, being separated from the last three chambers mentioned by an imperforate portion 30 of the partition wall 34, but open to the string chamber through a slot 35. The slot 35 is designed to provide for the extrusion of the spacing clips 15. These clips, one of which is shown in detail in Fig. 5, each consists of a pivoted member adapted to seat 35 in a recess 36 formed in the spacing bar when in inoperative position but to be biased toward a position perpendicular to the spacing bar by means of a spring 37.

40 The clips are formed with a slot 50 which embraces the string 9, enabling the clips to support the weight of the loaded string. To prevent this weight tilting the spacing bar laterally and causing it to bind against the 45 walls of the chamber in which it slides, the spacing bar is provided with thrust rollers 51.

There are a number of these spacing clips, 50 arranged at spaced intervals which have been found proper for the maximum spacing of the tobacco leaves. The top of the spacing bar is formed with a plurality of ratchet teeth 38, which teeth are arranged to be in the path of the pawl 28 carried by 55 the shuttle when said pawl is in operative position. Said pawl will hereinafter be referred to as the pushing pawl for its function is to advance the spacing or rack bar when the shuttle advances, providing 60 that there is tobacco in the feed chamber at the time of the advance of the shuttle.

When the spacing bar is in position of 65 repose, it lies next to the imperforate portion of the partition wall 34, the spacing clips 15 being held confined within the recesses 36

by the proximity of said imperforate portion. The spacing bar is normally biased toward this position by means of the spring 39, being advanced step by step from said position by reciprocatory movements of the 70 shuttle.

The spacing bar chamber is provided, at least in that part which lies adjacent the shuttle, feed, and needle chambers with an upper wall, the same lying beneath the path 75 transversed by the pawl 28 when it lies in inoperative position. When said pawl is tripped by engagement of the tobacco with the nose 52 the end of it contacts with said upper wall and slides upon it until an elongated aperture 30 is reached. This lets the nose of the pawl into the ratchet teeth 38, and further advance of the pawl while within said slot moves the spacing bar a distance equal to the length of the remainder of the 85 stroke of the shuttle, which, normally is equal to the distance between two spacing clips. After each step by step movement, the spacing bar is held against return by a holding pawl 41 fixed to the frame, which 90 also engages the ratchet teeth 38. When the spacing bar has been advanced to its full extent, that is to say, to the full length of the string chamber, the holding pawl falls down into a recess 42, adjacent the rearward end 95 of the spacing bar, being thereby released so that the spacing bar returns at once to its position of repose under the urge of the spring 39. The pawl then drops over the forward edge of the spacing bar in readiness 100 to perform its function as soon as it rides up on the teeth of said bar under the initial advance movement of the latter. It is clear that whenever there is tobacco in the feed chamber, reciprocation of the shuttle will 105 cause operation of the spacing mechanism, but that when there is no tobacco in the feed chamber the nose 52 will not be pushed back and the pushing pawl 28 will remain inoperative. Thus there will be no idle operation 110 of the spacing mechanism, nor will there be any vacant places on the string.

It will be observed from Fig. 1 that the imperforate portion of the partition wall 34 extends to the point 43 which is just beyond the eye of the needle 8, but to the rear of the outward limit of the range of travel of the shuttle. It is at this point that the spacing clips begin to swing outwardly through the slot 35 into the path of the tobacco so that each clip assumes an extended position behind the leaf or leaves of tobacco which have just been deposited upon the string by the shuttle, and upon the advanced movement of the spacing bar, it pushes said leaf or leaves 120 forward the required distance.

It is sometimes desired to space the tobacco a less distance apart on the string than is provided by the spacing clips so that provision is made for letting two or more leaves 130

or bundles of leaves onto the string between each pair of spacing clips. This is accomplished by shortening the stroke of the shuttle in any suitable manner, as for instance, by shortening the length of the crank 14. Under such circumstances the spacing bar will be advanced a correspondingly reduced distance at each stroke, placing a leaf of tobacco upon the string each time, but the spacing clips will not appear in extended position until the spacing bar has been advanced the normal distance.

Momentum of the tobacco may be counted upon to slide it along the string some distance ahead of the stopping point of the shuttle. This is of no moment when the shuttle is operating in unison with the interval between the spacing clips, for no matter where a tobacco leaf may slide under such conditions, it is the only leaf, or bundle of leaves between two clips and will inevitably move by the rearward of said clips to a position determined by the stopping point of said clip upon cessation of the advanced movement of the spacing bar, but when the length of the shuttle bar is regulated to introduce two or more leaves or bundle of leaves between a pair of spacing clips, momentum of the tobacco at the end of the shuttle stroke is apt to cause the leaf or leaves of the tobacco to bunch up together, without any semblance of uniform spacing. My invention therefore contemplates the provision of means, independent of the spacing clips, for inhibiting the inertia movements of the tobacco leaves so that they become uniformly spaced upon the string according to the uniform strokes of the shuttle and without reference to the spacing clips.

This attachment preferably consists of a small casing 44 adapted to be arranged on top of the frame 1, and supporting a sliding yoke which is positioned to descend to a point at which it straddles the string 9, just in advance of the outward limit of the shuttle stroke. This yoke is normally suspended in inoperative position by means such as the spring 66 which is stretched by a cable 67, attached to the inner end of a plunger 45, the latter being arranged in the path of the shuttle, and to be struck thereby. The cable 67 passes over suitable direction changing pulley 47. When the plunger is pressed inwardly of the casing by the shuttle, the yoke is lowered to a position in which it inhibits the momentum of the tobacco. Upon the return stroke of the shuttle the plunger and attached cable are urged in the opposite direction by contraction of the spring 66, quickly lifting the yoke to inoperative position. This attachment is not necessary when the machine is operating with the length of advance movement produced by the shuttle stroke equal to the distance between the spacing clips.

Having described my invention what I claim as new and desire to secure by Letters Patent, is:—

1. In a tobacco stringing machine, a stationary needle carrying a string at one end, supporting means engaging said needle at a plurality of longitudinal points, means for impaling a tobacco leaf upon said needle and pushing it the full length of said needle upon the string beyond, said supporting means being constructed to yield away from said needle at successive points, and means carried by the impaling means to engage and move the needle supporting means away from the needle for passage of the tobacco. 70

2. In a tobacco stringing machine, a stationary needle carrying a string at one end, a plurality of resiliently mounted supporting means engaging said needle at a plurality of longitudinal points, means for impaling a tobacco leaf upon said needle and pushing it the full length of said needle, upon the string beyond, and means carried by the impaling means to engage the resilient supporting means and move the same away from the needle for passage of the tobacco. 80

3. In a tobacco stringing machine, a stationary needle carrying a string at one end, a plurality of pairs of oppositely arranged supporting means engaging said needle longitudinally, the pair adjacent the point of said needle converging in the direction of travel of the tobacco to assist as a guide in directing the tobacco to the point of said needle, means for impaling a tobacco leaf 95 upon said needle, and pushing it the full length thereof, upon the string beyond, and means carried by the impaling means to engage and move the supporting means away from the needle for passage of the tobacco. 100

4. In a tobacco stringing machine, a stationary needle carrying a string at one end, a plurality of pairs of oppositely arranged resilient supporting means having ends embracing said needle longitudinally, the pair adjacent the point of said needle converging in the direction of travel of the tobacco, means for impaling a tobacco leaf upon said needle and pushing it the full length thereof upon the string beyond, the forward tobacco engaging face of said impaling means being substantially V-shaped and co-operating with said convergent pair of supporting means for allocating said tobacco in the path of the needle point, and means carried by the impaling means to engage and move the supporting means away from the needle for passage of the tobacco. 110

5. In a tobacco stringing machine, a stationary needle, a string carried thereby in tensioned relation axially of the needle, means for supporting said needle and preventing endwise yielding of the same to the tension of said string, comprising a plurality of pairs of oppositely arranged resilient 125

- ly mounted supporting means embracing needle longitudinally, some of said supporting means being provided with projections extending laterally through holes in said 65
5 needle, means for impaling a tobacco leaf upon said needle and pushing it the full length of said needle upon the string beyond, said supporting means successively yielding to the pressure of suitable engaging
10 means to permit passage of the tobacco, and immediately reengaging said needle after passage of said tobacco so that some of said projections are at all times in some of said lateral holes.
- 15 6. In a tobacco stringing machine, a stationary needle, a string carried thereby in tensioned relation axially of the needle, means for supporting said needle and preventing endwise yielding of the same to the
20 tension of the string, comprising a plurality of pairs of oppositely arranged resiliently mounted supporting means, embracing said needle longitudinally, the supporting means of some of said pairs having projections ex-
25 tending oppositely through lateral holes in said needle, means for impaling a tobacco leaf upon said needle and pushing it the full length of said needle upon the string beyond, said supporting means successively
30 yielding to the pressure of means carried by said tobacco impaling means, to permit passage of the tobacco, and immediately reengaging said needle after passage of said tobacco, so that some of said projections are at all times in some of said lateral holes, said
35 projections acting as cleaners for said holes.
7. In a tobacco stringing machine, a frame forming a feed chamber, a stationary needle at one side thereof carrying a string, spacing means operatively positioned with respect to said string, a shuttle at the other side of said feed chamber, and movable thereacross into telescopic relation to said needle, for impaling tobacco upon said
40 needle and pushing it beyond said needle, upon said string, means normally inoperative, carried by said shuttle for producing step by step advance of said spacing means, and means actuated by tobacco in said feed
45 chamber upon contact with said shuttle for rendering said advancing means operative.
8. In a tobacco stringing machine, a frame forming a feed chamber, a stationary needle at one side thereof carrying a string, a shuttle at the other side of said feed chamber, movable thereacross into telescopic relation to said needle, for impaling tobacco upon said needle and pushing it beyond said needle upon said string, spacing means op-
50 eratively positioned with respect to said
55 string, means normally inoperative, carried by said shuttle for producing step by step advance of said spacing means and means actuated by tobacco in said feed chamber, upon contact with said shuttle, for rendering said advancing means operative, said spacing means including a bar, and clips carried thereby successively extensible at each advance step of said spacing means behind successive deposits of tobacco made by said shuttle upon said string adjacent the
60 needle.
9. In a tobacco stringing machine, a frame forming a feed chamber, a stationary needle at one side thereof carrying a string, a shuttle at the other side of said feed chamber movable thereacross in telescopic relation to said needle for impaling tobacco upon said needle pushing it beyond said needle upon said string, shuttle actuated means operatively related to said string for inhibiting the inertia of tobacco thus deposited
65 and means for regulating the length of the advance steps of said spacing means.
